WOMAN'S PROTECTIVE HOSIERY AND
SHOE COVERING

Sophie Sabaneeff, New York, N. Y.

Application January 31, 1946, Serial No. 644,505

2 Claims. (Cl. 36—1)

1

This invention relates to a woman's protective hosiery and shoe covering.

It is well known in accordance with modern style open-toed shoes are extremely popular with women. If a woman inadvertently is caught in inclement weather, her hosiery becomes unsightly in appearance and the wearer oftentimes contracts a cold.

The principal object of the present invention is to provide a protective device of extreme simplicity which a woman may easily and quickly slip on before she goes out in stormy weather and one which will keep her feet dry and hosiery unsoiled. An additional object is to provide such a protective device which is extremely compact and light weight and may therefore be carried in a woman's purse or hand bag without occupying undue space so that if inclement weather should unexpectedly arise the woman may step into a sheltered place and don the protective covering.

Other advantages will appear evident as this specification proceeds. Referring to the drawings forming a part thereof and in which a preferred form of the invention is illustrated:

Fig. 1 is an elevational plan view showing the foot-portion with the protective enveloping portion spread out;

Fig. 2 is a perspective view of the protective hosiery and shoe covering;

Fig. 3 is a perspective view showing the shoe in position over the foot-portion of the protective covering before the enveloping portion has been applied;

Fig. 4 is a perspective view showing the protective covering completely applied;

Fig. 5 is a fragmentary perspective view of the forward part of the foot portion showing another form of the invention;

Fig. 6 is a fragmentary bottom plan view of the protective enveloping portion used in connection with the foot portion illustrated in Fig. 5; and

Fig. 7 is a fragmentary perspective view showing the form of the invention illustrated in Figs. 5 and 6 on the shoe of the wearer.

Referring again to the drawings and particularly to Figs. 1 to 4, the reference numeral 5 indicates the foot-portion of the protective device. As will be apparent, particularly from an inspection of Fig. 2, this foot portion is adapted to snugly fit over the toes and lower instep and extends around the lower heel and ankle portion of the wearer.

The foot-portion is preferably made of one piece 6 having an insert 7 for covering the lower

instep and toe portions. The insert 7 is secured in place by any well known method that will make a water-proof seam. In order to provide flexibility the upper portion of the insert over the instep is shirred as indicated 8. A loop 9 is formed on the upper part of the heel-portion, the purpose of which will hereinafter become apparent.

The foot-portion is formed of an extremely thin water-proof elastic plastic material. Due to the extreme thinness of the plastic material and its elastic qualities and the shirring 8 the foot-portion fits the wearer so snugly that it will cause no discomfort when the shoe is pulled over it.

At the toe end of the foot portion is a sheet of material 10, the nature of the material preferably being analogous to that used in the foot-portion. The sheet of material 10 may be formed as part of the insert 7 or it may be secured in any desired manner to the foot-portion in the region of the toe end. The material 10 is formed with a toe-portion 12 and its rear portion is provided with two pairs of loops 13—13 through which a strap 14 is adapted to pass. Due to the lightness of the material 10 it is easily drawn through the open toe portion 15 of the shoe prior to and while the shoe is being put on, as particularly illustrated in Fig. 3.

Fig. 4 shows the toe-portion 12 of the material 10 fitting over the toe of the shoe and the balance of the sheet folded about the shoe and instep of the wearer. It will be noted the strap 14 passes downwardly under the sole of the shoe adjacent the heel and thence around the foot in the ankle region where the ends are tied together as indicated at 16, thus properly positioning the enveloping protective material. The strap 14 passes through the loop 9 which aids in maintaining the two parts in proper relation to each other.

References now will be had to Figs. 5, 6 and 7 where similar reference characters denote similar parts. In this form of the invention the protective enveloping portion 20 is detachably secured to the foot-portion 5 so that if desired the foot-portion 5 could be used without the protective enveloping portion.

For this purpose a loop 21 is secured to the forward part of the toe-portion. Otherwise the foot-portion is identical to that described in the form of the invention illustrated in Figs. 1 to 4.

The protective enveloping portion 20 has a tab 22 secured to the toe-portion 12 thereof and the free end of the tab 22 has one part 23 of a conventional glove fastener secured thereto. In at-

taching the protective enveloping portion the tab 22 is passed through the loop 21 and the part 23 of the glove fastener engages its mating part 24 which is fastened to the protective enveloping portion in the region of the instep. Obviously other means might be utilized for detachably securing the protective enveloping portion to the foot portion.

The protective enveloping portion is provided at its lower peripheral region with a thickened portion 25. This thickened portion 25 encompasses the sole area of the shoe. It is form fitting and has sufficient inherent resiliency to hold it in contact with the shoe at the edge of the sole. A neat appearance is thus produced as the protective enveloping portion will be held snugly over the shoe and the exposed part of the hosiery in the instep and ankle regions. Otherwise the protective enveloping portion is similar to that described in connection with Figs. 1 to 4. It is to be understood the thickened portion 25 could be applied to the protective enveloping portion illustrated in Figs. 1 to 4.

I claim:

1. A protective covering for a shoe open at the toe end, comprising a member adapted to fit the lower part of the foot and made of an extremely thin water-proof elastic plastic material, and a sheet of material secured to the toe of said member and adapted to pass through the open toe end of the shoe to envelop the shoe and foot adjacent the ankle region to protect same, said sheet of material having a part shaped to cover the toe end of the shoe, loops attached to the rear part of said sheet of material, and a strap for passing through said loops and under the sole of the shoe and around the ankle to properly position said sheet of material.

2. A protective covering for a shoe open at the toe end, comprising a member adapted to fit the lower part of the foot within the shoe and made of an extremely thin water-proof elastic plastic material, and a sheet of material secured to the toe of said member through the open toe end of the shoe to envelop the front part of the shoe and foot adjacent the ankle region to protect same, said sheet of material having a part shaped to cover the toe end of the shoe, loops attached to the rear part of said sheet of material, and a strap for passing through said loops and under the sole of the shoe and around the ankle to properly position said sheet of material.
